P. E. EDELMAN

ORIENTED ELECTRICAL CONTACTOR

Filed Dec. 15, 1927

UNITED STATES PATENT OFFICE.

PHILIP E. EDELMAN, OF CHICAGO, ILLINOIS.

ORIENTED ELECTRICAL CONTACTOR.

Application filed December 15, 1927. Serial No. 240,215.

An object of my present invention is to increase the operating life of the oriented current conducting contactors.

A further object is to improve the operating efficiency and obtain a steady flow of current thru the contact surfaces free from undesired fluctuations.

A further object is to provide contact surfaces prepared so as to require no age treatment or forming for use.

A further object is to prepare the oriented current conducting contactors in stabilized form with the materials contacting prepared physically in a molecular form whereby the atoms comprised in the materials are combined in crystal form.

My invention is an improvement over rectifiers of the Pawlowski type and differs over prior art in the physical structure of the contact surfaces. Heretofore it has not been possible to obtain dry contact rectifiers entirely free from current variations due to inequalities in reverse current flow caused by incomplete action at the contact surfaces.

Since the initial discovery by F. Brau in 1874 that metallic sulphides are capable of asymmetric conductivity various improvements have been made. Reasonably satisfactory rectifiers have been constructed for small current output where fluctuations are unimportant but all known embodiments and improvements of the prior art have failed to provide properly stabilized contact surfaces. Thus when rectifiers are made according to the specifications of other patentees, such as S. Rubin, it is found that there is considerable reverse current flow thru the contacts. This causes undesirable operating characteristic in that this reverse current flow is not

steady in value but changes transiently from moment to moment as the contact surface breaks down and rebuilds itself. When such rectifiers are used in a radio power unit, the output tends to be unsteady, varying from one to three tenths of a volt momentarily. When first connected in circuit, such rectifiers consume much current in the reverse current flow and have a lower output, which builds up in a few minutes but does not reach an entirely steady value. Examination of the discs of such rectifiers shows that only a part thereof has been in active use and that the

current has jumped from one spot to another whenever a better path has been afforded during the transient physical changes in the contact surfaces.

I aim to overcome the transient variations principally by providing a permanently stabilized physical structure for the contactors at which rectification of current flow is accomplished. By providing proper physical structure, reverse current flow is steadied because a constant current path is provided at the junction of the contactors instead of a transiently variable path. Therefore the load on the feeding transformer for the rectifier becomes constant as regards the current consumption in reverse current flow instead of variable as in prior rectifier elements in which this reverse current flow is unsteady and draws more or less current from time to time, which causes the voltage to rise and fall according to the changes in the load on the feeding transformer.

I illustrate, by way of example, a suitable embodiment of my invention in the accompanying drawings in which Figure 1 is a diagram of a rectifier circuit employing my oriented contactors; Figure 2 is a sectioned front elevation of my oriented contactors embodied in a rectifier structure; Figure 3 is a sectioned front elevation of the combined metallic sulphide and metal structure I employ in my contact disc; Figure 4 is a front elevation of the crystalline alloyed physical surface combined on the positive contact disc of my rectifier; Figure 5 is a sectioned view showing the preparation of the negative contact discs; and Figure 6 is a diagram showing the preparation of the crystallized metal positive contact discs.

Various changes and modifications may be made without departing from the spirit of this invention and within the scope of the appended claims.

Referring now to Figure 1, a transformer 1 supplies current to a full wave rectifier 2 which consists of oriented contactors 14, 15; 16, 17; 18, 11; and 12, 13 arranged like a double pole double throw switch connection as is customary in this art. The output terminals are, positive terminal 8, and negative terminal 9.

Each particular pair of contactors as for

example 14, 15 are comprised by an electro-negative compound surface 14 combined with an electrode 7, with 14 pressing against an electronegative crystallized metallic surface 15 alloyed on positive electrode 3. The other contactors and electrodes are similarly arranged in pairs and interconnected in correct polarity as designated by numerals 19, 16, 17, 6; 21, 18, 11, 20; and 4, 12, 13, 5; it being understood that additional contactors may be employed in series or parallel connection as is customary in this art.

For a particular instant current can flow from transformer 1 to a load circuit connected at terminals 8 and 9 via 3, 15, 14, 7; and 21, 18, 11, 20, assuming that no reverse current can flow. However such is not the case and there is at the same instant a possible circuit from the transformer 1 via either the pathway 20, 11, 18, 21; 6, 17, 19, 16 or the pathway via 4, 12, 13, 5; wire 10, and 7, 14, 15, 3. The amount of current leaking thru such reverse current pathways depends on various factors and I aim principally to maintain same at uniform instead of transiently fluctuating values. Suppose for a particular time instant that load current is flowing as stated and that leak current is also flowing as indicated. Then if the leak current should increase transiently the transformer 1 must not only supply the load current and the normal leak current, but also the increase in leak current. Such increase on the transformer output terminals 22 causes the voltage at such terminals to drop with resulting fluctuation at output terminals 8 and 9. A similar action occurs at each reversal of polarity in transformer 1 during each cycle and thru the particular contacts of rectifier 2 concerned, also in the particular leakage pathways concerned for each instant. From such considerations it appears that since leakage current cannot be entirely avoided, my conception of providing steady values for the leakage current instead of transiently varying values provides a practical solution of the difficulty. This is accomplished by providing a correct physical structure for the oriented current carrying contactors so that the leakage current path is uniform and is attained as herein set forth.

It is manifest that uniform flow of reverse current as distinguished from load current thru rectifier 2 cannot be had with any physical structure for the oriented contact elements which requires continual breaking down and building up to maintain the oriented contactors in operative relation. Thus in Pawlowski, U. S. Patent No. 830,924, Sept. 11, 1906, typical of one type of physical structure for the contacts, the oriented action requires a transfer of electrons from the positive element and negative element under the influence of the current flow which sets up sufficient heat to cause minute sparking ac-

companied by a continual change in chemical or electrochemical recombination of the elements at the contact surface. This condition is unstable and while suitable for battery charging purposes, gives rise to fluctuations in the output potential when used in a true battery eliminator filter circuit device. Similarly, the other type of contact structure of which the U. S. patents to Rubin Nos. 1,649,742 and 1,649,743 or 1,649,744 of November 15, 1927, are typical, attempt to improve on Pawlowski, cited, by supplying a prepared non-crystalline surface on the positive electrode. However, it is established that rectification or current orientation only occurs at a true crystalline junction and such latter type of contactors depend for their action on a subsequent partial building up and breaking down of a crystalline junction surface, which also depends on current flowing to cause sufficient thermal and chemical or electrochemical action to set up an acting physical crystalline oriented junction between the positive and negative contactors. Such latter type is also found to vary in output, as may be expected from consideration of this action and while the action may be stabilized to an extent by an aging process the reverse flowing current is likely to change in amount at any particular time depending on the condition of the crystalline structure at the contact junction at any instant. However by providing a permanent crystalline structure at the contact surfaces in accordance with my invention, the need for the said breaking down and rebuilding of the crystalline nature of the contact junction, necessary for real oriented contacts, is avoided and while there will be some leakage current it will have a steady pathway afforded therefor via said permanent crystalline contact surface and not need to rebuild new pathways along the electrode surface from time to time. Thus, whereas in the prior art only a temporary and partial crystalline structure has been indirectly attained at the active junction of the oriented contacts, I provide a permanent prepared crystalline active junction over the entire contacting surface of the contacts and on both the positive and negative contacting elements.

Supporting evidence for this essential theory of contact surfaces will be found in the book Principles of Wireless Telegraphy by G. W. Pierce, McGraw Hill Pub. Co., Wireless Telegraphists Pocket Book by J. A. Fleming, the Wireless Press Ltd. London 1915; L. W. Austin, Bulletin of Bureau of Standards No. 94, Vol. V, 1908, Washington, D. C.; W. D. Eccles, Proceedings Physical Society of London Vol. XXV 1913, as well as in the Pawlowski patent hereinbefore mentioned.

Referring to Figure 2, a suitable series assembly of pairs of oriented contactors for a half wave rectifier element is shown. A

bolt 25 carries an insulating sleeve 23 and a yielding insulating washer 24. Negative contact electrodes 35, 31; 34, 30; and 33, 29 are alternately disposed on sleeve 23 between 5 positive contact electrodes 41, 38; 40, 37; and 39, 32 which are also carried on sleeve 23. A thermically expansible washer 26 causes the positive and negative contactors aforesaid to press together when nut 27 is tightened permanently on bolt 25. Washer 26 may be made from an alloy containing antimony and tends to equalize the pressure at extremes of temperature due to its property of expansion. The yielding washer 24 cooperates to maintain 15 approximately uniform pressure on the said electrode contacts. The operating terminals of the rectifier shown in Figure 2 are the positive metal electrode 32, and the negative metal electrode 31. All negative electrodes, 20 as for example 35, 31 are constructed similarly; and all positive elements, as 41, 38 are similarly constructed alike. The negative electrode or disc is shown separately in Figure 3, and the positive electrode unit 25 is shown separately in Figure 4.

In Figure 3, a copper washer 44 has a terminal 28 formed therewith. Washer 44 can be of any suitable electronegative metal, and copper is suitable. The washer 44 is thermo-chemically coated with an electronegative compound of the metallic material of washer 44 combined with a non-metallic element; a suitable composition for this coating 43 being either copper sulphide CuS or Cu_2S . Or a selenide of copper is also suitable. It is also permissible to intermix some metallic or powdered copper in the crystal mass 43. The terminal portion 28 of washer 44 is required only on units as shown in Figure 3 which are 35 to serve as terminals to an external circuit and may be omitted on other discs like 44 to which no external circuit is directly connected. A convenient manner in which to apply terminal 28 is to scrape away sufficient of the material 43 to permit soldering or welding strip 28 to metal washer 44.

A suitable manner for preparing elements as in Figure 3 is indicated in Figure 5. The orifice 42 of washer 44 is also coated with material 43 by this method, but the washer 44 is not entirely chemically converted to form the material 43, its inner base 44 remaining true metallic copper. This metallic core 44 assists in heat conduction from the electrode coating 43 of Figure 3 as well as giving it mechanical strength to prevent cracking of the brittle crystalline homogeneous coating mass 43.

A crucible 45 is shown in Figure 5 heated 60 by a gas flame 49. A fire clay cover 46 is luted on crucible 45 by cement 47 to prevent air leakage therein. A layer of flowers of sulphur 48 is spread in the bottom of crucible 45. Over sulphur 48, which should be of pure 65 grade, a refractory layer 50 is placed. This

layer 50 may consist of dry powdered alum-dum cement or any other refractory material which does not react with sulphur or copper when heated. A plurality of copper washers 51 are cleaned and prepared from electro-lytically refined copper in soft or semi-hard sheet stock about $\frac{1}{16}$ " to $\frac{3}{32}$ " thick. These washers 51 are stacked, out of contact with each other in crucible 45, with the refractory material 50 spread thereon and therebetween. The refractory material 50 appears to have beneficial property of distributing the thermo-chemical reaction evenly. The cover 46 is first secured over crucible 45 and then heat is applied from source 49 for a short time to melt the sulphur 48 and vaporize it. The sulphur vapor thus produced spreads thru the interior of crucible 45 and reacts with the copper metal pieces 51.

The amount of deposit on washers 51 can be controlled by regulating the temperature and time of treatment. Thereafter the crucible is cooled, the contents removed, and the coated washers 51 are cleaned and polished. The treatment should not be allowed to convert all of the copper in the washer, it being desirable to retain the inner portion of washer 51 unattacked by the sulphur so as to reinforce the finished contact element, as the sulphide coating itself is brittle. Emery or other abrasive material is suitable for polishing the discs 51.

The washers retain their original flat form by this treatment and do not buckle out of shape. As an example, a small crucible can be heated for as brief a time as five minutes to afford sufficient treatment to the discs 51, while a large crucible will require more time to complete the reaction. Obviously this treatment can be varied by initially dipping the discs 51 in a paste of powdered copper and powdered sulphur or a paste containing powdered selenium crushed from fused sticks of selenium. It is also permissible to first alloy the copper used for washers 51 with a small portion of zinc or tin before applying the treatment in crucible 5. Or the copper on washers 51 which is to be converted to copper sulphide may first be plated to a suitable thickness by electroplating said copper on a soft steel washer base. The coating obtained has a bluish black color but other colorings can be obtained by varying the proportions and time of treatment ranging from greenish black color to a deep blue corresponding to different proportions of combination. The bluish-black colored material is suitable for use and is principally crystalline copper sulphide CuS with possibly some Cu_2S also present. The crystalline structure in the mass is evident and is uniformly obtained by this treatment.

The positive contact element indicated by Figure 4 preferably comprises a sheet magnesium washer 53 having a terminal portion 130

52 formed therewith and an orifice 54. The crystalline coating 55 is applied by plating a deposit of magnesium metal thereon to combine as an alloy with washer 53, the coating 55 being physically converted to crystalline form intimately adherent to disc 53. Disc 53 can be some other metal than magnesium, if properly cleaned before coating 55 is applied thereto.

- 10 A suitable treatment to produce positive electrodes, as in Figure 4, is indicated in Figure 6. A roll of sheet magnesium 56 is fed over and under a series of rollers 63. In passing thru tank 57 the magnesium is first cleaned by a cleaning fluid 60 comprising diluted hydrofluoric acid, then washed in tank 71 with hot water continuously replaced by fresh water. In passing thru tank 58 the magnesium sheet is electroplated with an electro-alloyed deposit of magnesium. Tank 58 contains a suitable electrolyte including a salt of magnesium such as magnesium monophosphate, magnesium chloride or magnesium nitrate acidified, as is customary in 25 the plating art; and electrode 73 of metallic magnesium connects with battery 65 to feed the plating current to the sheet magnesium 75 by brush contact 64. A washing tank 74 permits the sheet magnesium to pass to container 59 where a blast of warm air is supplied via pipe 76 to dry the sheet 75 and rubbing electrodes 66 insulatively mounted on support 59 serve to transfer alternating current to sheet 75 from transformer 68. Transformer 35 68 feeds alternating current to sheet 75 by means of brush contact 77 and rubbing contactors 66. The sheet 75 is then cut by shears 69 and stamped into washers by die 70 to form completed contact elements 72.
- 40 Magnesium resembles zinc in its property of crystallizing when electro-galvanized onto a metallic surface. The size of the crystals can be regulated by controlling the treatment and regulating the current density. The potential applied by transformer 68 should also be proportioned to obtain the smaller sized crystals, as can be determined by experiment according to the rate at which roll 56 is used. By suitable care and precautions in keeping 45 sheet aluminum clean, aluminum sheet can be plated and prepared with crystallized magnesium coating in similar manner.

The prepared positive contact elements should be promptly assembled immediately after production thereof as the crystalline magnesium coating is likely to collect a coating of oxide if left standing for a period before assembling same for use. Crystalline magnesium will be recognized by its bright 50 crystalline appearance, whereas magnesium which has collected oxygen from the air will have a dull appearance.

I have now set forth fully my conception and described suitable means for attaining the objects set forth. This invention con-

cerns the product, which may be prepared as specified or by any other suitable process or method.

I claim;

1. A rectifying device consisting of a pair of oriented electrical contactors comprising an electropositive metallic electrode having a crystallized metallic surface alloyed thereon, and an electronegative metallic electrode having a chemically combined electronegative compound of a non-metallic electronegative element coated thereon, the contact junction being located between said crystallized metallic surface and said non-metallic coated element.

2. A rectifying device consisting of oriented electrical contactors comprising a crystallized metal surface plated on a positive electrode and an electronegative compound of a non-metallic element chemically combined with a supporting negative electrode, and means to press said crystallized metal surface against said electronegative compound.

3. A rectifying device consisting of oriented electrical contactors consisting of crystallized magnesium metal alloyed on the surface of a positive electrode, and a cooperating metallic sulphide contacting therewith and chemically combined with a negative metallic electrode.

4. A rectifying device consisting of oriented electrical contactors consisting of a positive contact element comprised by a metal electrode on which crystalline metallic magnesium is electro-alloyed, and a negative contact element touching said crystalline metallic magnesium of said positive contact, said negative element contacting only with said crystalline magnesium and not directly with the supporting metal electrode therefor.

5. A rectifying device consisting of oriented electrical contactors, one of which consists of a metal electrode having a crystallized metallic magnesium surface thereon, and a cooperative negative electrode pressed thereon and consisting of a sulphide of copper combined chemically with metallic copper.

6. A rectifying device consisting of electrical contactors consisting of positive and negative electrodes pressed together, said positive electrode comprising a crystallized metallic magnesium surface carried on a metal disc, and said negative electrode comprising a homogeneous crystalline mass of a sulphide of copper chemically combined on a metallic copper disc.

7. A rectifying device consisting of electrical contactors consisting of positive and negative electrodes, a crystalline surface of metallic magnesium alloyed on said positive electrode, and a crystalline mass of a compound of copper chemically combined with an electronegative non-metallic element ther-

mochemically formed on said negative electrode.

8. A rectifying device consisting of oriented electrical contactors consisting of a positive electrode having a crystallized surface of metallic magnesium thereon and a negative electrode pressed into intimate contact with said crystallized surface and consisting of an electronegative metal having a

homogeneous interlocked mass of copper sulfide thermo-chemically formed thereon, the terminals for said electrical contactors being firstly the positive electrode, and secondly the said electronegative metal. 10

In witness whereof I have hereunto set my 15 hand this 12th, day of December, 1927.

PHILIP E. EDELMAN.
